BOWL OR SIMILAR ARTICLE

Joseph B. Stier, New York, N. Y.

Application November 1, 1952, Serial No. 22,092

Term of patent 14 years

(Cl. D44—15)

To all whom it may concern:

Be it known that I, Joseph B. Stier, a citizen of the United States of America, residing in New York city, county of Kings, and State of New York, have invented a new, original, and ornamental Design for a Bowl or Similar Article, of which the following is a specification, reference being had to the accompanying drawing, forming part thereof, wherein:

The dominant feature of my design resides in the rim portion of the bowl.

I claim:

The ornamental design for a bowl or similar article, substantially as shown and described.

JOSEPH B. STIER.
